UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

CONTAINER.

1,233,063.

Specification of Letters Patent. Patented July 10, 1917.

Application filed September 19, 1916. Serial No. 120,967.

To all whom it may concern:

Be it known that I, JOSEPH KOMOROUS, a citizen of the United States, residing at Chicago, in the county of Cook and State of Illinois, have invented a new and useful Improvement in Containers, of which the following is a specification.

My invention relates, more particularly, to improvements in containers, forming the 10 casing or housing of the operative parts of a self-winding or self-rewinding tape-measure and formed, generally stated, of cover-sections with a substantially circular wall interposed therebetween and secured to these 15 sections, with an opening in the said wall through which the free end of the tape-measure extends; though I do not wish to be understood as intending to limit certain features of my invention to a container 20 forming a part of a tape-measure, as it may be embodied in containers of the general character above stated, but provided for other purposes.

As a preface to the following description, 25 it may be stated that where the cover-sections of the container are covered with celluloid or other material, which is common in practice, the inturned edges, or flanged portions of the covers produced by crimping 30 the same, are so bulky, if the container is to be made of such proportions that it would be economical to manufacture and be neat in appearance, that the proper interlocking of the covers with the wall-portion of the 35 container cannot be effected, whether this wall-portion be of metal or of other material, such as celluloid, and this is especially true in the case of containers forming parts of tape-measures of the type above referred 40 to, wherein the substantially circular wall contains a relatively wide slot for the tape. Again, in structures of this character, where the part forming the substantially circular wall of the container is of celluloid, or other 45 relatively flexible material, and even where the covers are not provided with a covering of celluloid, or the like, interlocking of the covers with the said wall has not been effectively accomplished, owing to the tendency of the celluloid to give in the crimping 50 operation.

My primary object, generally stated, is to provide a novel, simple and economical construction of container in which the substantially circular wall, and, preferably in tape-

measures, of the type above referred to, may be constructed of metal, celluloid or other desirable material and interlocked with the covers of the container, whether they be provided with a covering of celluloid, or the like, or are uncovered, without the use of 60 separate fastening devices, cement, or the like.

Referring to the accompanying drawings,—Figure 1 is a perspective view of a tape-measure of the self-rewinding type and embodying my improvements. Fig. 2 is an enlarged plan section of the device of Fig. 1, the section being taken immediately below the lower edge of the flange of the top 65 cover, as indicated at the line 2 on Fig. 3 and viewed in the direction of the arrow, the tape in this view being shown as withdrawn from the container or casing of the measure to the fullest extent. Fig. 3 is a 70 section taken at the line 3 on Fig. 2 and viewed in the direction of the arrow; and Fig. 4, a view in side elevation of the rotatable spring-actuated drum or can of the measure, showing the manner of attaching 75 the spring and tape to the can, the tape being broken away.

The container or casing of the tape-measure comprises cover-sections 5 and 6, spaced apart, and a substantially cylindrical wall-portion 7 extending into the space between said cover-sections and secured thereto, as hereinafter described, to form a substantially cylindrical casing or container for the operative parts of the measure, hereinafter 80 described. In the particular construction illustrated, the cover-sections 5 and 6 each are formed of a metal disk 8 provided with an annular flange 9 about its circumferential margin, with a covering 10 of celluloid 85 which completely covers the outer surface of the disk 8 and its flange 9 and extends over the inner surface of said flange, and, preferably, part way across the inner surface of the disk; and a liner 11 which is 90 located within the disk 8 and extends at its outer circular margin preferably into close contact with the celluloid at the base portions of the flange 9. These liners 11 which 95 preferably fit flatwise against the inner surfaces of the adjacent disks 8 at their central portions, as indicated at 12 and are outwardly offset, as indicated at 13, to provide an annular offset guide-portion 14, for 100 the purpose hereinafter described, are pro- 105 110 115

vided closely adjacent to their outer circumferential margins; but slightly inset therefrom, with annular shouldered portions 15, for the purpose hereinafter described. The 5 wall 7, which by preference is formed of celluloid, is, in the construction illustrated, provided as a strip of celluloid, with its parallel lateral portions flanged, as indicated at 16, though these flanges would not extend 10 at as great an angle to the body-portion of the strip carrying them before being assembled with the other parts shown in Fig. 3, as the angle shown in this figure.

The liner 11 for the lower cover 6, in the 15 particular construction illustrated, is provided with upwardly-extending means for engagement with the end of the coil-spring represented at 17 to hold this end rigid with the casing, these means, in the construction illustrated, comprising two prongs 18 which are bent up from the metal of the lower liner 11. The spring 17 which is located within the can, hereinbefore referred to and represented at 19, and which fits fairly 20 closely between the surfaces 14 of the upper and lower liners 11 and has an opening 20 through which the prongs 18 extend, is interlocked at its convoluted inner end portion 21 with the prongs 18 as illustrated in 25 Fig. 2 and is coiled around itself within the can 19, with its outer end interlocked with the circular wall 22 of the can. To provide an attachment of this end of the spring to the can in the desired relation to the tape for 30 likewise securing the latter to the can, I provide in the circular wall 22 three slots 23, 24 and 25. The outer end of the spring 17 is bent, as indicated at 26, to extend at 35 its extremity through the slot 24 and at the angular portion 27 at which it is bent, in 40 the slot 23, the outer extremity of this end of the spring extending adjacent the inner side of the wall 22 between the slots 24 and 25 therein. The tape having graduations 45 thereon, is represented at 28, this tape extending through a slot 29 provided in the circular wall 7 of the casing, and which is preferably provided by employing a strip of material to form this wall, of such length 50 that when assembled with the cover-sections the ends thereof will reach short of each other a distance sufficient to provide this slot of the desired width. The inner end of the tape 28 extends through the slot 25 into the 55 interior of the can 19, thence outwardly through the slot 23, across the outer face of the wall 22, and thence inwardly through the slot 24 to cause its extremity to extend adjacent the inner side of the wall 22, the 60 section of the tape just referred to where it passes through the slots 23 and 24 being confined between the section of the wall 22 between these slots and the adjacent portions of the spring 17, which causes the tape to be 65 firmly clamped to the can 22. To further

insure against disengagement of the tape from the can 19, I prefer to so arrange the parts of the device, as shown, that the rotation of the can in the movement thereof under the action of the spring, to rewind the 70 tape on the can, is in the direction of the arrow in Fig. 2, and thus the additional clamping action afforded by the bending of the tape in a direction back upon itself augments the security of the fastening. It will 75 be understood that the tape 28 winds upon the circular wall 22 of the can under the action of the spring 17, when the operator after drawing the tape to the position shown in Fig. 2, discontinues pulling on the same. 80

The parts of the structure are preferably assembled in the following manner:

The liner 11 of the cover 6 is inserted to the position shown in Fig. 3. The strip to form the circular wall 7 is then curled to 85 general circular shape and inserted at one of its flanged edges into the space between the flange 9 and the annular surface 15, the flanges 16 of the strip extending outwardly. The parts thus assembled are then introduced into a suitable die-press and the flanged portion 9 of the cover 6 crimped over to the position illustrated in Fig. 3 in which it interlocks the parts 7, lower cover 6 and liner 11 together, as illustrated in Fig. 3. 90 The can 19, with the spring 17 and tape 28 attached thereto, as hereinbefore described, and upon the encircling wall 22 of which the tape 28 has been preliminarily wound, is then introduced into the space afforded by 100 the encircling wall 7, the prongs 18 extending upward through the opening 20 in the can and interlocking with the convoluted end 21 of the spring (Fig. 2), the spring by 105 preference being under slight tension in this position. In assembling the parts, as stated, the outer end of the tape 28 would be positioned within the slot 29. The upper plate 8 and the liner 11 therefor are then applied to the upper flanged portion of the wall 7 110 and the flanged portion 9 of the top cover crimped by introduction into a die-press, into the position shown in Fig. 3 for interlocking the plate 8 and liner 11 of this upper cover with the upper flanged portion of 115 the wall 7.

It will be noted that the portion 15, serves as a backing for the strip forming the wall 7, and thus even if the latter be of a material which tends to flex comparatively 120 readily, it will be held by the surface 15 in such position that the flange of the cover may be crimped or otherwise bent into the desired interlocking engagement therewith. This is of special advantage where the material of which the wall 7 is formed is celluloid, and especially when the plates 8 are provided with a covering such as the covering 10, of celluloid, and more especially where 125 the tendency of the wall 7 to flex is augment- 130

ed by the provision of a slot like the slot 29 which is of relatively great width. This feature, however, is of advantage where the wall 7 would be made of sheet metal, and where the 5 parts of the cover-sections, which would be turned back for interlocking with the flanges of the wall 7, would be so bulky that the proper crimping of the metal against the flanges of the wall 7 for producing the desired interlocking could not be effected because of the flexing of the wall 7. The disks 10 11 besides affording the backing for the wall 7, as stated, serve to reinforce the disks 8 and thus permit of the latter being made of relatively thin material.

While the feature above described and relating to the container portion of the device was designed, more particularly, for a tape-measure, and presents its greatest advantage, so far as I now know, in a construction of this character, I do not wish to be understood as intending to limit the invention to this particular use, nor do I wish to be understood as intending to limit my invention to the particular embodiment illustrated and described, as various modifications and alterations may be made therein without departing from the spirit of my invention.

30 What I claim as new and desire to secure by Letters Patent is—

1. A container formed of cover-sections, and an intermediate curved surrounding wall-section flanged at its opposite edges, said 35 cover-sections being formed of disks having flanges interlocked with the flanges on said wall-section, and means adjacent the inner surface of said wall-section and arranged at the opposite edges of the latter and forming a 40 backing for said wall-section to prevent the latter from crushing or collapsing in the operation of interlocking said flanges.

2. A container formed of cover-sections, and an intermediate curved surrounding 45 wall-section flanged at its opposite edges, said cover-sections being formed of disks having flanges interlocked with the flanges on said wall-section, and shoulders on said cover-sections adjacent the inner surface of 50 said wall-section, forming a backing for the latter.

3. A container formed of cover-sections, and an intermediate curved surrounding wall-section flanged at its opposite edges, 55 said cover-sections being formed of disks having flanges interlocked with the flanges on said wall-section and annular shoulders on said cover-sections adjacent the inner surface of said wall-section forming a backing for the latter.

60 4. A container formed of cover-sections, and an intermediate curved surrounding wall-section flanged at its opposite edges, said cover-sections being formed of disks 65 having flanges interlocked with the flanges

on said wall-section, and provided with means adjacent the inner surface of said wall-section forming a backing for the latter.

5. A container formed of cover-sections, and an intermediate curved surrounding 70 wall-section flanged at its opposite edges, said cover-sections being formed of disks having flanges interlocked with the flanges on said wall-section, and disks provided adjacent their marginal edges with shoulders 75 adjacent the inner surface of said wall-section forming a backing for the latter.

6. A container formed of cover-sections, and an intermediate curved surrounding wall-section flanged at its opposite edges, 80 said cover-sections being formed of disks having flanges interlocked with the flanges on said wall-section, and disks provided adjacent their marginal edges with annular shoulders adjacent the inner surface of said 85 wall-section forming a backing for the latter.

7. A container formed of cover-sections, and an intermediate curved surrounding wall-section flanged at its opposite edges, 90 said cover-sections being formed of disks having flanges interlocked with the flanges on said wall-section, and disks confined between said first referred to disks and said wall-section and held in place by the interlocking of said flanges, said last-named disks being provided adjacent their marginal edges with shoulders adjacent the inner surface of said wall-section forming a backing 95

100 for the latter.

8. A container formed of cover-sections and a curved surrounding wall-section flanged at its opposite edges said cover-sections being each formed of two disks, one of which is flanged and is interlocked with the adjacent flange on said wall-section, and the other of said disks of each cover-section being offset toward the center of the container within its marginal edges and forming a shoulder, said shoulders being located adjacent the inner surface of said wall-section and forming a backing for the latter.

105 9. A container formed of a cover-disk, and having a curved surrounding wall-section having an outwardly-turned flange at 115 an edge thereof, said disk having a flange surrounding the flange on said wall-section and interlocked therewith, and a disk permanently retained in the container and provided adjacent its marginal edge with a shoulder adjacent the inner surface of said wall-section forming a backing for the latter to prevent crushing or collapsing of said wall-section in the operation of interlocking said flanges.

120 125 10. A container formed of a cover-disk, and a curved surrounding wall-section having an outwardly-turned flange at an edge thereof, said disk having a flange surrounding the flange on said wall-section and in-

terlocked therewith and a disk permanently retained in the container and provided adjacent its marginal edge with an annular shoulder adjacent the inner surface of said wall-section and forming a backing for the latter to prevent crushing or collapsing of said wall-section in the operation of interlocking said flanges.

11. A container formed of a cover-disk, 10 and a curved surrounding wall-section having an outwardly-turned flange at an edge thereof, said disk having a flange surrounding the flange on said wall-section and interlocked therewith, and a disk confined between said first-referred-to disk and said wall-section and held in place by the interlocking of said flanges, said last-named disk being provided adjacent its marginal edge with shouldered portions adjacent the inner 20 surface of said wall-section forming a backing for the latter.

12. A container formed of a cover-disk, and an intermediate curved surrounding wall-section having an outwardly-turned flange at an edge thereof, said disk having a flange surrounding the flange on said wall-section and interlocked therewith, and a disk confined adjacent the inner surface of said first-named disk and reinforcing the 30 same, and having a portion thereof located adjacent the inner surface of said side wall and forming a backing for the latter.

13. A container formed of a cover-disk, and a curved surrounding wall-section having an outwardly-turned flange at an edge thereof, said disk having a flange surrounding the flange on said wall-section and interlocking therewith, and a disk having an offset portion forming an annular shoulder, said disk being confined between said first referred to disk and said wall-section with the flanged portion of said wall-section fitting flatwise against the portion of said second-named disk beyond said shoulder and the body-portion of said wall-section fitting against said shoulder, said last-named disk being held in place by the interlocking of said flanges. 35 40 45

14. In a container formed of a cover-disk, and a curved surrounding wall-section having an outwardly turned flange at an edge thereof, said disk having a flange surrounding the flange on said wall-section and interlocked therewith and a disk permanently retained in the container and provided adjacent its marginal edge with an annular shoulder off-set relative to the periphery of said last-named disk and extending adjacent the inner surface of said wall-section and forming a backing for the latter to prevent crushing or collapsing of said wall-section in the operation of interlocking said flanges. 50 55 60

JOSEPH KOMOROUS.
